UNITED STATES PATENT OFFICE

DONALD K. SINGER, OF HARTFORD, CONNECTICUT, ASSIGNOR TO THE B. F. GOODRICH COMPANY, OF NEW YORK, N. Y., A CORPORATION OF NEW YORK

BUFFING APPARATUS

Application filed June 8, 1928. Serial No. 283,960.

This invention relates to buffing apparatus and especially to apparatus such as is used in the rubber industry for buffing the skived ends of straight tubes of vulcanized rubber preparatory to the splicing of said ends in the manufacture of inner tubes for pneumatic tires.

In the manufacture of inner tubes by the aforementioned method, one end of the tube is buffed on its outer face and the other end on its inner face, the latter operation being accomplished while the tube-end is cuffed or turned back upon itself, which operation heretofore has resulted in numerous defective tubes due to the fact that frequently the buffing wheel was allowed to operate past the skived end of the tube with the result that it buffed the underlying tube structure and caused a thin spot therein.

The general object of this invention is to avoid the production of defective inner tubes due to weak spots caused by faulty buffing. More specifically its object is to provide improved apparatus for the buffing of the inner surface of the end of a rubber tube.

Of the accompanying drawing:

Fig. 1 is a side elevation of buffing apparatus embodying my invention in its preferred form.

Fig. 2 is a section on line 2-2 of Fig. 1.

Fig. 3 is a fragmentary plan view of parts of the apparatus shown in Fig. 1, and the work operatively associated therewith, a part being in section and broken away.

Referring to the drawing, 10 is a table or base-plate upon which is mounted a journal bracket 11 for a horizontal shaft 12, the latter being connected at one end with suitable driving means such as the motor 13, and having its other end provided with an abrasive buffer herein shown as a wire scratch-brush 14.

Pivottally mounted at 15 upon a bracket 16 rising from the base-plate 10 is an upwardly extending arm 17 having its free end formed with a laterally extending arcuate plate 18

constituting a shield or spacer member which is disposed tangentially with relation to the periphery of the brush 14. A tension spring 19 having its ends connected to the arm 17 and base-plate 10 respectively is provided for normally urging the arm 17 rearwardly away from the brush 14 and such rearward movement is limited by a stud 20 extending from the bracket 16 and abutted by a radial lug 21 formed on the arm adjacent its pivot 15.

In the operation of the apparatus a rubber tube, such as the tube 22, which is to have the inner face of its end portions buffed, is mounted, with said end portion cuffed or turned back as shown in Fig. 3, upon a short form or mandrel 23 which is rotatably mounted upon a spindle 24 provided with a handle 25. The operator then mounts the cuffed portion of the tube upon the shield 18 in such a manner that the shield is disposed between the body portion of the tube and overlying cuff, and the two portions of the tube are held in spaced-apart relation at least in the region of the brush's operation upon the cuffed portion. He then moves the assembly into engagement with the brush 14, and by rotating the form 23 upon its spindle 24 progressively presents the entire marginal portion of the tube to the rotating brush 14 to effect the buffing thereof.

As will be seen with reference to Fig. 3, the shield 18 at all times is positioned between the brush 14 and the underlying wall of the tube and spaces the two apart so that abrasion of the latter is avoided, because of the spacing and also because of the presence of the member 18 as a shield, although the brush extends beyond the marginal portion of the tube. Also, the invention enables inexperienced operators to produce work of a quantity and quality comparable to that heretofore produced by experienced workmen.

My invention is susceptible of modification within the scope of the appended claims.

I claim:

1. Apparatus for buffing a flexible portion of a rubber article situated adjacent an exposed underlying portion thereof, comprising a rotary buffer and a short arcuate member positioned to support the portion to be buffed and to shield the adjacent underlying portion of the article, said member being mounted for movement toward and away from said buffer radially of the latter.
- 5 2. Apparatus as defined in claim 1 comprising yielding means urging the supporting and shielding member away from the buffer.
- 10 15 In witness whereof I have hereunto set my hand this 31st day of May, 1928.

DONALD K. SINGER.
